DESIGN FOR A PICTURE FRAME CHANNEL

Irving Greenfield, New York, N. Y.

Application March 27, 1941, Serial No. 99,924

Term of patent 3½ years

To all whom it may concern:

Be it known that I, Irving Greenfield, a citizen of the United States of America, residing in New York city, county of New York, and State of New York, have invented a new, original, and ornamental Design for a Picture Frame Channel, of which the following is a specification, reference being had to the accompanying drawing, forming part thereof, wherein,

Figure 1 is a front view of a picture frame channel showing my new design.

Figure 2 is an end elevational view thereof.

Figure 3 is a perspective view of one half of the front and side of the picture frame channel shown in Figure 1; and

Figure 4 is a perspective view of the opposite half and side thereof.

I claim:

The ornamental design for a picture frame channel, substantially as shown.

IRVING GREENFIELD.
